UNITED STATES PATENT OFFICE.

CECIL HAMELIN TAYLOR, OF DETROIT, MICHIGAN.

INTERNAL-COMBUSTION ENGINE.

1,330,408.

Specification of Letters Patent. Patented Feb. 10, 1920.

Application filed April 27, 1918. Serial No. 231,156.

To all whom it may concern:

Be it known that I, CECIL HAMELIN TAYLOR, a citizen of the United States, residing at Detroit, county of Wayne, State of Michigan, have invented a certain new and useful Improvement in Internal-Combustion Engines, and declare the following to be a full, clear, and exact description of the same, such as will enable others skilled in the art to which it pertains to make and use the same, reference being had to the accompanying drawings, which form a part of this specification.

My invention relates to internal combustion engines and an object of my improvements is to provide an improved arrangement of the valve-ports and passages leading thereto.

I secure this object in the device illustrated in the accompanying drawings in which;

Figure 1 is a plan view of the removable head of a multi-cylinder engine.

Fig. 2 is an elevation looking from the right of Fig. 1 showing also a portion of the upper end of the cylinder casting.

Fig. 3 is an elevation of the part shown in Fig. 1.

Fig. 4 is a plan view of the cylinder casting with the cylinder head removed.

Fig. 5 is a sectional elevation on the broken line E—E Fig. 1.

a is a cylinder casting and b is a removable cylinder head. The cylinders are cast ^{en bloc} and there are four cylinders contemplated in the device shown. d is a projection from the center of the cylinder head which extends over the side of the engine and has a horizontal machined surface at its outer end to which the carburetor c (Fig. 2) is secured.

e is the intake passage which enters the cylinder head at the horizontal surface on the outer end of the projection d, rises up into the cylinder head, extends inward toward the center thereof, and branches into two forks e² e³. Each of these forks turns downward and opens in a passage e⁴ through the machined surface forming a part of the lower and engaging surface of the cylinder head.

The cylinder head is hollowed out below to form an extension of the cylinders at e⁵ and the space e⁵ for the inlet valve g and the exhaust valve h which are respectively actuated through valve stems g² and h².

j j j j are the cylinders formed in the casting a. Between the pairs of cylinders there is a downwardly extending passage f which opens upward through the machined ⁶⁰ uniting upper surface of the cylinder casting, extends horizontally in said casting and then opens upward in the intake port f² to the space e⁵ in the cylinder head. f³ is a port opening from the space e⁵ to the exhaust discharge passage f⁴. ⁶⁵

When the cylinder head b is placed upon the casting a the opening e⁴ from the passages e² and e³ register with the passages f f in the casting a thus forming a continuous ⁷⁰ intake port through the passage e, the forks e² e³, the passage f, the port f² and into the space e⁵ which communicates with the cylinder j around the wall of the part e⁴ of the intake passage. ⁷⁵

By reference to Fig. 5 it will be seen that the intake passage, or the branches e² e³ thereof, pass over the cylinders and are separated therefrom by a common wall which forms the lower wall of said passage. ⁸⁰

What I claim is:

1. In an internal combustion engine, the combination of a cylinder casting having a passage opening downward therein and turning and again opening upward, a cylinder head having an intake passage therein opening downward through its lower surface and adapted to register and form a continuous passage with the downwardly opening passage in said casting, said casting ⁸⁵ having a cylinder formed therein, said head being provided with a concavity opening upward from its lower surface adapted to communicate with said cylinder and with the upward opening from the passage in ⁹⁰ said casting, and an inlet valve controlling the opening from the passage in said casting. ⁹⁵

2. In an internal combustion engine, the combination of a cylinder casting having a passage opening downward therein and turning and again opening upward, a cylinder head having an intake passage therein opening downward through its lower surface and adapted to register and form a continuous passage with the downward opening passage in said casting, said casting having a cylinder formed therein, said head being provided with a concavity opening upward from its lower surface adapted to communicate with said cylinder and with the upward opening from the passage ¹⁰⁰ ¹⁰⁵ ¹¹⁰

in said casting, and an inlet valve controlling the opening from the passage in said casting, a second passage in said casting opening downward from the concavity in the cylinder head and outward to form an exhaust passage, and an exhaust valve controlling said second passage.

3. In an internal combustion engine, a cylinder casting having cylinders therein, a separable head from said cylinder, said cylinder casting having an upper joining surface and said cylinder head having a lower joining surface, a passage in said cylinder head opening downward through the joining surface thereon, a passage in said casting opening downward from the joining surface thereon and forming a continuation of the passage in the cylinder head, the passage in said casting opening upward, means for connecting the upward opening portion of the passage in the casting with the cylinder, and a valve controlling the upwardly opening passage in said casting.
4. In an internal combustion engine, a cylinder casting having cylinders therein, a separable head from said cylinder, said cylinder casting having an upper joining surface and said cylinder head having a lower

joining surface, a passage in said cylinder head opening downward through said joining surface thereon, a passage in said casting opening downward from the joining surface thereon and forming a continuation of the passage in the cylinder head, the passage in said casting opening upward, means for connecting the upward opening portion of the passage in the casting with the cylinder, and a valve controlling the upwardly opening passage in said casting, said means consisting in a cavity having a portion of its wall in common with the intake passage.

5. In an internal combustion engine, the combination of a cylinder casting having a passage opening downward therein and turning and again opening upward, a cylinder head having an intake passage therein communicating with the passage in said cylinder casting to form a continuous passage therewith, said casting having a cylinder formed therein, the passage in said casting communicating with said cylinder, and an inlet valve controlling the opening from the passage in said casting to said cylinder.

In testimony whereof I sign this specification.

CECIL HAMELIN TAYLOR.
